(57) CLAIM

The ornamental design for a bed frame and headboard set as shown and described.

DESCRIPTION

FIG. 1 is a front perspective view of a bed frame and headboard set in accordance with our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a section view thereof along line 8-8 of FIG. 1; and,

FIG. 9 is a section view thereof along line 9-9 of FIG. 1.

The portions of the bed frame and headboard set shown in broken lines form no part of the claimed design.

1 Claim, 8 Drawing Sheets(56)
